Primary Examiner — Susan E Krakower(74) *Attorney, Agent, or Firm* — Robert Lauson; Lauson & Tarver LLP(57) **CLAIM**

I claim the ornamental design for an exercise device, as shown and described.

DESCRIPTION

FIG. 1 is a perspective view of the exercise device according to the new design.

FIG. 2 is a front view thereof.

FIG. 3 is a top view thereof; and,

FIG. 4 is a bottom view thereof.

The broken lines showing illustrate portions of the exercise device which form no part of the claimed design.

1 Claim, 2 Drawing Sheets*FIG. 1*

FIG. 2

FIG. 3

FIG. 4
